UNITED STATES PATENT OFFICE.

MANUEL BOUZO, OF HABANA, CUBA.

ELECTRIC HEATING APPARATUS.

1,273,451.

Specification of Letters Patent. Patented July 23, 1918.

Application filed December 18, 1916. Serial No. 136,605.

To all whom it may concern:

Be it known that I, MANUEL BOUZO, a citizen of the Republic of Cuba, residing at O'Reilly St., Number 67, Habana, Cuba, 5 have invented new and useful Improvements in Electric Heating Apparatus, of which the following is a specification.

This invention relates to electric heating apparatus, and its object is to provide an 10 apparatus which is highly efficient for the rapid heating of the water, and supplying the hot water in a continuous and uninterrupted stream. Another object is to provide a water heater which is adapted to an 15 electric circuit of 110 volts just as much as to one of 220 volts.

The invention is described with reference to the figures of the annexed drawing, in which:

20 Figure 1 is a side elevation, partially broken away, of an electric heating apparatus constructed according to this invention.

Fig. 2 is a vertical central sectional view thereof,

25 And Fig. 3 is a transverse sectional view taken on line 3—3 of Fig. 2.

This heater consists of a casing or double jacket formed of two iron tubes 1, 1', although it can be of any electrical conducting 30 or non-conducting material whatsoever. These tubes are closed at their opposite ends, by two plugs 2 and 3 made of an insulating paste, and in these two plugs there are inserted, one within the other, two concentric 35 tubes 4 and 5 made of an electrical conducting material, such as iron. As clearly shown in Fig. 2, the walls of the tubes 4 and 5 are spaced apart in parallelism. The central tube 5 has one end thereof inserted in an 40 aperture 6 formed axially within the lower plug 3. The central tube 5 has near its upper end a lateral hole 7 which establishes communication between the interior of said tube 5 and the space 8 intermediate between 45 the two tubes 4 and 5. The tube 4 is formed near its lower end with two lateral holes 9 which establish communication between the space 8 and the space 10 intermediate between 50 the tube 4 and the inner tube 1 of the outer casing. The holes 9 are of greater diameter than the hole 7 of central tube 5. On the lower threaded end of tube 1' is 55 screwed a cap 11 made of metal or of any other suitable material, such cap being formed with a central bushing 12 in which is threaded a pipe 13 which serves to estab-

lish communication with the interior of the central tube 5 with water supply pipes, not shown. On the upper threaded end of tube 1' is screwed a metallic cap 14, formed with 60 a central bushing 15 and into which is inserted an insulator ring 16 through which pass two conducting cables or wires 17 and 18 which carry the electric current from any appropriate supply. These cables are connected to terminals 19 and 20 on the conducting tubes 5 and 4 respectively, whereby the electric current is transmitted to the two tubes 4 and 5. In the inner tube 1 of the double jacket there is threaded in a lateral aperture 21 arranged in radial alignment with the communicating hole 7, an overflow pipe 22 which passes through a corresponding aperture in the outer tube 1'. At a point diametrically opposite to aperture 21 there is connected with tube 1 a pressure counterbalancing pipe 22' which passes through a respective aperture in the outer tube 1' of the double jacket and is opened to the atmosphere at its upper end. 70 75 80

The operation of the apparatus is as follows: The water that enters through the lower pipe 13 will penetrate into the central tube 5 and pass through the upper hole 7 to the space 8 intermediate between the two 85 tubes 4 and 5, descending through said intermediate space down to the lower part thereof, wherefrom it goes out through the holes 9 and then passes to the space 10 located between the tube 4 and the outer double 90 jacket tube 1. Since tubes 4 and 5 are conducting tubes or electrodes, the electric current will pass between the inner surface of outer tube 4 and the outer surface of inner tube 5 through the particles of mineral salts 95 in the water interposed between the walls of both tubes. These particles of salts act as metallic resistances that become heated and transmit their heat to the surrounding water and the walls of inner tube 5 and outer 100 tube 4. Thus the water that arrives from the central tube 5 will be heated when passing therethrough by virtue of the contact with its wall. The water that comes out through holes 9 to the space 10, and rises up 105 through this space to be discharged through the overflow pipe 22 is heated by contact with the outer wall of the exterior conductor 4. Communication with the atmosphere is established by tube 22', permitting the hot 110 water to discharge through the overflow pipe 22 in a continuous stream. The tem-

perature of the discharged water is nearly that of boiling water which is due to the fact that the apparatus is constructed so that the water receives the maximum amount of the heat produced by the electric current and to the gradual heating of the water, since same is slightly heated before same is subjected to the action of the electric current between the two electrodes, and 10 in which latter state it is favored as electric resistance. It will be observed the circulation of the water through the interior of the apparatus follows a zig-zag path through its whole length.

15 Preferably for a circuit of 220 volts I use one hole 7 and two diametrically opposed holes 9, as indicated in Fig. 3 of the drawings, but for a circuit of 110 volts two holes 7 are used which establish communication between the central tube 5 and tube 4, and three holes 9 spaced equidistant apart and establishing communication between the conducting tube 9 and the double jacket inner tube 1.

20 25 It is obvious, therefore, that the number of communicating holes between the two conducting tubes and between these and the double jacket casing can widely vary, as well as the form of this casing, without materially altering the spirit of the invention, which is as pointed out in the appended claims.

What I claim is:

1. An electric liquid heater comprising an outer casing, an inner casing insulated from the outer casing, a cylindrical electrode within said inner casing and spaced and insulated therefrom, a second cylindrical electrode within the first electrode and spaced and insulated therefrom, an inlet pipe communicating directly with the inner electrode, an outlet pipe extending through

said outer casing and communicating with the inner casing, the first electrode being formed with opposed openings adjacent its lower end and the second electrode being formed with an opening adjacent its upper end, to permit longitudinal circulation of a liquid from said inlet pipe to and through said electrodes and into said outlet pipe. 45 50

2. An electric liquid heater comprising an outer casing, an inner casing insulated from the outer casing, a cylindrical electrode within said inner casing and spaced and insulated therefrom, a second cylindrical electrode within the first electrode and spaced and insulated therefrom, an inlet pipe communicating directly with the inner electrode, an outlet pipe extending through said outer casing and communicating with the 60 inner casing, said electrode being perforated to permit circulation of a liquid from said inlet pipe to and through said electrodes and into said outlet pipe, and a steam outlet pipe communicating with said inner 65 casing at a point adjacent to the upper end thereof.

3. An electric liquid heater comprising a liquid tight casing, a pair of electrodes mounted in said casing and insulated from each other and from said casing, means for circulating a liquid between and exteriorly of said electrodes, and means for preventing back pressure in said casing whereby the circulation of the liquid will be rendered 75 continuous and uninterrupted.

In testimony whereof I have signed my name to this specification in the presence of two subscribing witnesses.

MANUEL BOUZO.
